UNITED STATES PATENT OFFICE

SAMUEL A. GRAVES AND NELSON MUSLAR, OF WORCESTER, MASSACHUSETTS

IMPELLING DEVICE FOR GAMES

Application filed December 2, 1930. Serial No. 499,524.

This invention relates to a device or stick for use in games, in which a ball is projected over a game board or the like, for shooting the ball.

The principal objects of the invention are to provide a game stick of this kind having means by which, when the operator moves an operating element, no matter whether he presses on it slowly or rapidly, a plunger will be shot forward by spring pressure to impel the ball; to provide means whereby the amount of spring pressure employed and therefore the energy imparted to the stroke will not be under the control of the operating device but will be adjustable by other means; to provide means whereby the motion of the operating means will first compress the actuating spring and then release it; to provide means whereby the drawing back of the operating element will again set the whole device ready for its next operation and to provide a novel ball which can be made of the desired weight in proportion to its volume in order to make it just as lively as may be desired and no more so.

Other objects and advantages of the invention will appear hereinafter.

Reference is to be had to the accompanying drawings, in which

Fig. 1 is a central vertical sectional view of a playing implement constructed in accordance with this invention and showing the improved ball, the parts being at rest;

Fig. 2 is a similar view showing the implement in the position just ready to operate;

Figs. 3 and 4 are two similar views of a modified form, and

Figs. 5 and 6 are similar views of two other forms.

The implement is intended for use in any kind of a game in which a ball or puck is driven over a board or the like, but is particularly adapted for use as a golf stick for parlor golf games and also for so-called miniature golf. Of course, the stick is made in different sizes according to the game that is to be played. The idea is to provide an operating element which can be moved rapidly or slowly and in either case the same impact will be given to the ball. The adjustment of the

stroke is secured in another way as will appear.

Referring first to Figs. 1 and 2, the golf stick there shown is provided with a hollow handle 10, which may be long enough to reach to the ground from the hands of the person standing, if it is to be used in ordinary miniature golf, but is made much smaller if it is to be used for a table game of golf or other game. This is in the form of a tube having at the bottom a hollow cylindrical horizontal head 11. In the tube there is an operating element 12 projecting from the top thereof and there is a partition 13 secured to the handle 10 by one or more projections 14. On the top of the partition 13 is a compression spring 15 and a rod 16 secured to the operating element 12 and projecting freely down through the spring and partition 13 serving as a guide for keeping the spring from buckling.

On the bottom of the rod 16 is an operating plunger 17 having a notch 18 provided with an inclined lower surface 19. As will appear later, this notch cooperates with a lever 20 having a projecting operating end 21 with an inclined lower surface 22 and slanting upper surface 23. This lever is pivoted on a stud 24 and has an end 25 which extends into a notch 35 in a hammer head 26 which impels the ball. The head 26 is located in the hollow cylindrical head 11 of the stock and is guided by the interior thereof and is provided with a reduced end 27 which projects through the end of the head of the stock and impels the ball. Behind the head 26 is a coiled compression spring 28 and a screw cap 29 fits on the end of the head 11 and can be screwed out and in to adjust the compression of the spring 28. On the other end there is a cap 30 which is perforated to receive the reduced end 27 of the head 26 and is also screwed in position on the head 11.

We have shown a ball 31 which is provided with a spherical cavity in the center containing mercury 32. This cavity is completely filled with mercury and the mercury is introduced through an opening 33 which is plugged up later. The ball is of any desired kind of wood. The reason for making this ball of wood and weighting it is that the

ordinary ball, even if made of the heaviest wood, is too light when used on a small game board or the like. When a ball is desired which is heavier than wood, other materials might be selected but we find that the weight of the ball in comparison to its volume is very easily controlled by this part of the invention.

In the form shown in Figs. 3 and 4 the rod 16 is extended down to provide a controlling plunger 36 which has an end 37 provided with a trapezoidal outline, a slanting surface 38 at the top and a slanting surface 42 at the rear. In this case the plunger 39 is hollow and cylindrical and provided with a slot 40 for this operating end 37. The rear wall of this slot is slanting at 41, as shown and the plunger 36 is forced down to allow the rear end of the head 37 to pass under the slanting surface 41 when the spring 28 will force out the plunger 39. The distance that it can be forced out is limited by the engagement of the front end of the surface 41 against the lower end of the rod 36. This slanting surface 41 is of the same slant as the rear surface 42 of the head 37 so that when the rod 36 is forced down the plunger 39 will first be forced back as shown in Fig. 3. The surface 38 is made slanting so that when this plunger 36 is pushed downwardly it will force the plunger 39 back to the position shown in Fig. 4 before it lets it snap forward.

It will be seen therefore that in both cases the cap 29 can be adjusted to control the energy with which the stroke is delivered and that in the form shown in Figs. 1 and 2 the cap 30 can be adjusted to control the length of the stroke. The operating button or member 12 is pushed down and the energy with which the stroke is delivered is not controlled in any way by the rapidity of depression of this operating member. The parts are easily set after being operated by pulling this operating member 12 upwardly. The device has few parts and the ball can be made to have the desired amount of weight and no more.

The form shown in Fig. 5 is similar to that shown in Figs. 3 and 4 but more desirable. The head 47 is vertical at the back and is horizontal on top. The horizontal plunger is recessed and has a slanting surface 48 sloping in a direction opposite to the surface 41. A collar 43 on the rod 46 is so located as to limit the upward motion of the rod 46 so that the head 47 never rises to the top of the slope 48.

In Fig. 6 the parts 10, 11, 12, 13, 14, 15, 16, 26 and 35 are the same as in Fig. 1, except that the cylinder 11 has no adjustable cap and is open at one end. A plunger 57 has a spring trigger 50 provided with a projection 51 having oppositely slanting upper and lower surfaces. As the plunger 57 is pushed down it snaps into an opening 58 and oper-

ates the plunger 26. The adjustment is secured by a screw 52 which acts as an adjustable stop.

Although we have illustrated and described only a few forms of the invention we are aware of the fact that other modifications can be made therein by any person skilled in the art without departing from the spirit of the invention as expressed in the claims. Therefore, we do not wish to be limited in this respect but what we do claim is:

1. In an impelling device for the purpose described, the combination of a plunger for delivering a blow, a spring behind the plunger for forcing the plunger forward, means for holding the plunger in position for delivering a blow, hand-operated means by which the plunger is forced back to compress the spring and then, by the same movement of the operating means, released to deliver the blow and means for resetting the plunger when the hand-operated means is withdrawn to normal position.

2. An impelling device for the purpose described comprising a hollow stick and operating member at the top thereof, a horizontal plunger at the bottom, a spring behind the plunger for forcing it out to deliver a blow, means for holding the plunger back against the compressed spring and means operated by said operating member for releasing the holding means and allowing the plunger to be forced forward by the spring.

3. An impelling device for the purpose described comprising a stick and an operating member at the top thereof, a horizontal plunger at the bottom, a spring normally pressing said plunger, a lever connected with the plunger for holding it back and compressing the spring and means operated by the operating member for suddenly releasing the lever and thereby freeing the spring.

4. An impelling device for the purposes described comprising a stick and an operating member, a horizontal plunger, a spring normally pressing said plunger, a lever connected with the plunger for holding it back and compressing the spring, means operated by the operating member for suddenly releasing the lever and thereby freeing the spring for projecting the plunger, and means for adjusting the space within which the spring is compressed.

5. An impelling device for the purpose described comprising an operating member, a horizontal plunger, a spring behind the plunger for forcing it out to deliver a blow, means for holding the plunger back against the compressed spring, means operated by said operating member for releasing the holding means and allowing the plunger to be forced forward by the spring, and a screw cap on the end of said head adapted to be adjusted in and out to control the energy with which the spring will operate the plunger.

6. In an impelling device of the character described, the combination of a hollow stick, a rod slidable therein, a spring, an operating member slidable in the top of the stick and connected with said rod and also resting on the top of said spring, a plunger fixed to the lower end of said rod and having a recess therein, a transverse head at the bottom of said stick having a cylindrical passage therethrough, a plunger movable in said passage, a spring in the head tending at all times to force the plunger outwardly, said plunger having a notch, and a lever having an end projecting into the notch for controlling the plunger and having an upper end adapted to enter the notch in the first named plunger.

7. In an impelling device of the character described, the combination of a hollow stick for use in moving the impelling device around and manipulating it, having a partition across the same inside, a rod slidable through the said partition, a spring supported by the partition above it, an operating member slid-
20 able in the top of the stick and connected with said rod and also resting on the top of said spring, a plunger below the partition on the lower end of said rod and having a recess therein with a slanting lower side, a trans-
25 verse hollow head at the bottom of said stick having a cylindrical passage therethrough, a plunger movable in said passage, a spring in the head tending to force the plunger out-
30 wardly, and a lever for controlling the plunger and having an upper end adapted to enter the notch in the first named plunger and provided with a slanting lower surface by which the slanting surface of that notch will force back the upper end of the lever when the operating member is raised to reset
35 the device.

40 In testimony whereof we have hereunto affixed our signatures.

SAMUEL A. GRAVES.
NELSON MUSLAR.
